IDAHO.

CONDENSER.

1,111,242.

Specification of Letters Patent. Patented Sept. 23, 1914.

Application filed November 18, 1913. Serial No. 801,889.

To all whom it may concern:

Be it known that we, GEORGE C. SUTTON, ISAAC W. CROWL, and JOHN O. HAMBERG, citizens of the United States, residing at 5 Priest River, county of Bonner, and State of Idaho, have invented certain new and useful Improvements in Condensers, of which the following is a specification.

This invention relates to condensers.

10 The object of the invention is to provide a condenser of novel construction which is adapted for condensing from the products of combustion, particularly those derived from a stump, the valuable products carried 15 by the products of combustion treated by the condenser.

Our invention consists in the novel condenser whether used in connection with the stump burning apparatus, or, in any connection where it is necessary or desirable to employ a condenser for products of combustion.

20 In the accompanying drawings: Figure 1 is a perspective showing the condenser in use in connection with a stump burner; and 25 Fig. 2, a vertical section through the condenser.

In our co-pending application, Serial No. 761231, we have claimed apparatus for conducting internal combustion in the stump, 30 without regard to how valuable parts, such as tar, acids, etc., existing in the products of combustion are condensed and collected therefrom. Preferably, at or near the center of the stump 1 a hole 2 is bored down 35 from the upper face thereof, a suitable distance, say ten or twelve inches below the level of the earth outside the stump. Another hole 3 is then bored into the stump in a general lateral direction, commencing 40 about the level of the earth and inclined downwardly so that it will intersect the hole 2 at or near the lower end thereof. A fire is then started, by any suitable means or in any preferred manner at or about the point 45 2^a where the holes 2 and 3 intersect and the combustion is allowed to continue until the upper end part of the hole 2 has become slightly enlarged. A pipe 4, preferably of metal, and provided with any suitable air 50 valve or controlling device 5 at its outer part, is inserted in the hole 3 to within a few inches of where holes 2 and 3 intersect at 2^a. This pipe constitutes a draft pipe and the amount of air admitted to the fire 55 at 2^a may be regulated by the valve 5. At

or about the time the pipe 4 is inserted, a pipe 6, preferably of metal, and of suitable diameter, say two inches, more or less, is inserted in the hole 2 after the said hole 2 has become slightly enlarged at its top by 60 the fire. The pipe 6 is entered into the hole 2 to a distance within a few inches above the point 2^a, the upper end of the pipe extending above the top of the stump. A flat sheet of metal 7 is then fastened to the top 65 of the stump by nails or other fastenings 7^a, or otherwise positioned thereon and it is provided with any suitable means such as 7^b to engage the pipe 6 and prevent the latter from dropping. The plate or disk 7 70 prevents the fire from breaking out around the point where the pipe 6 passes through the upper face of the stump and also keeps the stump from burning to any appreciable extent above the lower end of the pipe 6 by 75 preventing draft through the previously exposed upper face of the stump. The foregoing steps having been taken, a hood or cover 8 of any desired form and preferably of metal, is placed around the stump and incloses it and the pipe 6 and plate 7, this hood 8 being preferably considerably larger than the stump to allow a free space between it and the stump. The hood is provided with a damper or valve 9 for the admission of 80 any desired amount of air to mix with the products of combustion coming out of the pipe 6 for the purpose of cooling such products of combustion and to render their subsequent condensation more rapid. 90

An elbow 10 connects the open upper end of the hood 8 to a generally laterally disposed pipe 11, said pipe and elbow 10 being preferably several inches in diameter. The pipe 11 is slightly inclined and provided 95 with a take-off faucet 12 from which the condensed liquids derived from the products of combustion may be drawn off, the inclination of pipe 11 causing such liquids of condensation to flow by gravity to the 100 tap or faucet 12. An elbow 10^a and an upright pipe 11^b pass the products of combustion into the lowest section of the condenser 13.

The condenser 13 is composed of an upper 105 section 13^a and a lower section 13^b which are preferably cylindrical, the upper section telescoping into the lower section and being supported thereby. The respective sections have closed upper and lower ends 14, 15. 110

The lower section has brackets 16 into which legs 17 are screwed. The legs may be of iron pipe. The lowermost section has a take-off pipe 18 controlled by a valve 19 through which the condensed liquids are drawn off from the condenser 13 independently of those drawn off by the faucet 12.

The respective sections 13^a, 13^b, have air draft tubes 20 extending therethrough from end to end, the ends of the tubes of one section telescoping at 21 with the ends of the tubes of the other section.

The lower section 13^b has a conical hood 22 arranged above the socket 23 which receives the end of pipe 11^b. As the products of combustion pass into the pipe 11^b and issue from the upper end thereof, they strike against the hood or baffle 22 and are spread downwardly and around the air draft pipes 20 and, due to the circulation of air through these pipes, the products of combustion are cooled and the condensable parts thereof, such as acids, tar, etc., fall to the bottom of section 13^b and may be drawn off through the pipe or spout 18. The non-condensable gases and the smoke pass from the condenser by a drop pipe 24 which is carried by the upper section 13^a and has its lower end 25 located a short distance above the hood 22. The smoke pipe 24 may be provided with a suitable valve or damper 26. As soon as the fire has gotten well underway in the center of the stump 1, the draft through the pipes 4 and 15 is partially cut off by regulating the valves or dampers 5 and 26. The stump then acts as a retort and the smoke and gases generated by the combustion therein pass into the pipe 11 and the condenser where they are condensed. The condensables may be taken off through the faucets or spouts 12 and 19.

The apparatus may be made in several sizes adapting it to stumps of different sizes. Disposing the condenser in lateral offset relation to the stump prevents it from becoming heated from the direct heat from the stump and assists in cooling and condensing the gases. The condenser may be enlarged to any desired extent by interposing between the upper and lower sections 13^a and 13^b, intermediate sections which have

no upper and lower heads, but are composed solely of draft pipes like the pipes 20, an extension of the pipe 24, and a surrounding shell.

55

Having thus described our invention, what we claim as new and desire to secure by Letters Patent, is:—

1. A sectional condenser composed of shells, tubes connecting said shells together, means for admitting products of combustion to the condenser, means for taking off smoke and non-condensable gases therefrom, and means for removing the condensables from said condenser.

65

2. A condenser composed of shells having air draft pipe sections, said shells and air draft pipe sections being fitted together, means for admitting products of combustion to the condenser, means for taking off smoke and noncondensable gases therefrom and means for removing the condensables from said condenser.

70

3. A condenser composed of a shell, air draft tubes extending therethrough, means for admitting products of combustion to the interior of the shell, a hood or baffle for spreading the products of combustion as they enter the shell, means for letting off smoke and noncondensable gases from the shell, and means for removing the condensables from said shell.

75

4. The herein described condenser consisting of shell sections having one end closed and the other end open, each section having an air draft tube, said tubes forming continuations of each other, means for taking off condensables from the condenser, means for taking off smoke and noncondensable gases, means for admitting products of combustion to the shell, and a hood or baffle for spreading the products of combustion as they enter the shell.—

80

In testimony whereof, we hereunto affix our signatures in presence of two witnesses. 95
